UNITED STATES PATENT OFFICE.

OSCAR S. MIERS AND EDWARD E. GENSLER, OF APPLETON, WISCONSIN.

ROCKING AND ROCKING-ARRESTING DEVICE.

1,151,212.

Specification of Letters Patent. Patented Aug. 24, 1915.

Application filed January 22, 1915. Serial No. 3,715.

To all whom it may concern:

Be it known that we, OSCAR S. MIERS and EDWARD E. GENSLER, citizens of the United States, residing at Appleton, in the county 5 of Outagamie and State of Wisconsin, have invented a new and useful Rocking and Rocking-Arresting Device, of which the following is a specification.

Our invention consists of a combined 10 child's carriage and cradle, and has for its object the conveniences of two necessary articles for the care of children, while the cost of two and the space required for the two is lessened and all of the advantages thereof 15 are retained, and the invention is shown in the accompanying drawing, in which,—

Figure 1 is a plan of a vehicle with a body mounted thereon, which body serves as a cradle, the bottom being broken 20 through. Fig. 2 is a side elevation of the same, the wheels nearest the observer being omitted. Fig. 3 is an end elevation of the inside of the forward bolster and its attachments. Fig. 4 is an end elevation of the out- 25 side of the rear bolster and springs, the body and wheels being omitted. Fig. 5 is an end elevation of the bolsters inclosed within their spacing stirrup.

Similar numerals indicate like parts in the 30 several views.

1, indicates axles of a child's carriage; 2, wheels thereon; 3, springs mounted upon the axles; 4, tie rods extending one to a pair of springs, each side of the vehicle for spacing the axles apart and connecting the 35 springs upon the forward axle to those upon the rear axle; 5, the lower member of the bolster; 6, the upper member, these being preferably formed of wood and the lower 40 member secured to the upper ends of the side springs 3 with rivets 7.

8 and 9 are upper and lower rocker members formed of band spring metal, and having each a convex rocking surface with its 45 ends returned toward each other, which ends are secured to the bolster with fastening rivets 7. 10 is a stirrup for spacing the bolster members apart and holding the rocker members in contact.

50 11 is a box or cradle member mounted upon the upper bolsters and secured thereto with screws 12. This box may be of any desired form as the taste of the maker decides upon.

55 The several parts being assembled in position and the two pairs of rocker members

compressed slightly between the bolster members by means of the stirrup 10, an easy transverse rocking movement can be produced by an attendant and the desired benefits of a cradle secured. 60

For arresting the rocking movement, which will be desirable when the vehicle is being moved from one place to another, frames are hinged to the lower member 6 35 with hinges 13, each consisting of two end pieces 14 and a rail 15. The rails are each provided with an ear 16, to which an operating rod 17 is connected at the forward rail, and to the rear rail by means of a link 70 18, which is connected to the rod 17 at 19, the link 18 having a link 20 extending from it to the rear rail 15.

Extending downward from the rear bolster members is an arm 21, having a slot 22, 75 through which the rod 17 and link 18 can freely move. Upon the outer end of the rod 17 a handle 23 is hinged at 24, it having at its lower end a notch 25 for engaging with the lower end of the arm 21 and holding the 80 rails 15 in engagement with the under side of the body 11 and arresting its rocking movement. From the free end of the link 18, a spring 26 extends to and is connected to the rear bolster member 6 and assists in 85 the operation of the rod 17. The ends 14, rails 15, rod 17, and links 18 and 20, as shown in heavy lines by their position, arrest the rocking movement of the box 11, but in their position in dotted lines permit 90 it to proceed. These swinging frames may be single or in pairs as desired.

No claim is made to the vehicle's construction as such.

Having described our invention, what we 95 claim and desire to secure by Letters Patent, is,—

1. A rocking device, consisting of two pieces of rigid material of a length greater than that of the rocking members spaced 100 and held intermediate their ends at a determined distance apart, two rocking members of spring band metal of similar form and dimensions, the ends of each member being bent and returned toward each other and secured to one of the aforesaid spaced apart members with the intermediate surface of said rocking members made convex and arranged in contact with each other and slightly compressed, one upon the other. 105

2. A rocking device, consisting of two pieces of rigid material of a length greater 110

than that of the rocking members spaced and held intermediate their ends at a determined distance apart, two rocking members of spring band metal of similar form and dimensions, the ends of each member being bent and returned toward each other and secured to one of the aforesaid spaced apart members with the intermediate surface of said rocking members made convex and arranged in contact with each other and slightly compressed, one upon the other, and a rocking movement arresting device, consisting of a hinged swinging frame having two ends and a connecting rail, said rail being arranged in the direction of the plane in which the rocking movement is being

made and adapted to engage the lower side of the part being rocked when said ends are swung into a nearly vertical position.

3. In a rocking device, a rocking movement preventive consisting of a swinging frame normally disengaged from the part to be rocked and arranged to swing in a plane at right angles with the plane of the rocking movement and to be engaged with the part being rocked for preventing the rocking movement.

OSCAR S. MIERS.

EDWARD E. GENSLER.
